ADJUSTABLE SOCKET

Filed April 30, 1928

Inventor
Cromwell A. B. Halvorson,
by Charles E. Muller
His Attorney

UNITED STATES PATENT OFFICE

CROMWELL A. B. HALVORSON, OF LYNN, MASSACHUSETTS, ASSIGNOR TO GENERAL ELECTRIC COMPANY, A CORPORATION OF NEW YORK

ADJUSTABLE SOCKET

Application filed April 30, 1928. Serial No. 273,804.

My invention relates to incandescent lamp sockets and especially incandescent lamp sockets of the type used in series lighting such as series street lighting.

5 In connection with the use of electric incandescent lamps it is very often important that the lamp should be adjusted with respect to other apparatus which modifies the light produced by the lamp, and the object of 10 my invention is to provide an improved adjustable lamp socket structure.

The invention will be more fully understood from the following specification and claims, reference being had to the accompanying drawings, in which I show a number of different forms of devices involving the features of the invention. It will be understood, however, that I do not wish to be limited to devices of the specific forms 20 shown, inasmuch as in view of the disclosure the devices may be modified without departing from the spirit of the invention or the scope of the claims contained herein.

Referring to the accompanying drawings, 25 Fig. 1 shows one form of device of the invention in perspective with adjustable plug terminals. Figs. 2, and 3 show in perspective modifications of the invention. Fig. 4 is a section through the device of Fig. 1 taken 30 on line 6—6. In this figure, however, the device is represented as being inserted in an independent socket, the latter being shown in the upper part of the figure, and in section also. Fig. 5 is a section on line 7—7 of the 35 clamp for the device, Fig. 2.

Referring first to Figs. 1 and 4, 2 indicates a lamp socket comprising a casing 22' of insulating material, a screw shell 29 of conducting material which forms one terminal 40 and a central contact 30 which forms the other terminal. The shell 29 and central contact 30 are held by contact screws 31 and 32. At "A" is indicated a plug comprising a base 6 of insulating material which carries 45 spring contacts 16 and 17 attached to the base by contact screws 18 and 19. Spring contacts 16 and 17 are adapted to be inserted between and to engage with the spring contacts 20 and 21 of a line receptacle "B" shown in Fig. 50 4. When in use, as is well known, contacts

16 and 17 are separated by a film of insulating material which breaks down upon being subjected to a predetermined high voltage, a film in the form of a disk 22, termed usually a "disk film cutout", being shown in Fig. 4 in the present instance.

The lamp socket 2, the line receptacle "B", and the arrangement for contacts 16, 17 and 21, 22 and their manner of engagement with each other are old and well known in connection with series incandescent street lighting structures, the constructions illustrated being the ones in common use.

My invention relates particularly to means for adjusting the lamp socket 2 whereby its position and hence the position of the lamp in the fixture may be adjusted, and according to my invention, I provide means whereby the distance between the plug contacts 16 and 17 and the lamp socket may be varied.

According to the embodiment of the invention shown in Figs. 1 and 4, I accomplish this result by providing contact strips 4 and 5 which are connected to the terminals of lamp socket 2 and contact strips 7 and 8 which are connected to the spring contacts 16 and 17 of plug "A", and so connecting the contact strips to each other that their combined lengths may be varied. For this purpose, contact strips 4 and 5 are provided with longitudinally extending slots 12 and 15 respectively, in which are located rectangular shoulders 11 and 14 adjacent to the heads of screws 9 and 12, the screws projecting through holes in contact strips 7 and 8 and being held by nuts 10 and 13. By loosening nuts 10 and 13, lamp socket 2 may be moved toward and away from plug "A", shoulders 11 and 14 sliding in slots 12 and 15, and fixed in adjusted position by again tightening the nuts. The contact strips 4 and 5 are held by contact screws 31 and 32 and the contact strips 7 and 8 are held by contact screws 18 and 19 so that strips 4 and 5 are

electrically connected to the lamp socket terminals and the strips 7 and 8 are electrically connected to the plug contacts 16 and 17. The circuit through the lamp is thus completed through strips 4, 7 and 5, 8.

Referring to the form of device shown in

Fig. 2, the construction is quite similar to that shown in Fig. 1. A modification, however, appears in the clamping element. The clamping element of Fig. 1 comprises two independent screws 9 and 12^a, whereas the clamping element of Fig. 2, as shown in detail in Fig. 5, is provided with a block of insulating material 23, which is provided with a central opening in which the heads 10 24 of the screws 25 and 26 are located. In the form of construction shown in Fig. 2 the plug contact elements 16' and 17' are held assembled by means of cleats 42 and 43 of insulating material, which cleats are held together by screws 44. In order to prevent the contact elements 16' and 17' from sliding on the socket terminals or strips 27 and 28 independently, the heads of the screws 24 and 25, as shown in Fig. 5, are interlocked by 15 means of the block 23 of insulating material as previously explained.

In order to limit the extent to which the plug contact elements 16' and 17' may be thrust into a socket element such as the socket 25 element B, Fig. 4, these elements 16' and 17' are provided with offset sections 45 which form a stop.

In the form of device shown in Fig. 3, the casing 33 of the socket is provided with terminals or strips 34 and 35 in the form of screws which carry, in threaded engagement therewith, corresponding spring plug contacts 36 and 37. The spring 36 is provided with a bracket structure comprising flanges 38 and 39 through which the screw 34 extends. The spring 37 is provided with a similar bracket structure comprising flanges 40 and 41 through which the screw 35 extends. Each of these contact springs 36 and 37 may 40 be adjusted on its screw support by being turned thereon. For example, the spring 36 may be rotated 180° to remove the spring 36 from engagement with the spring 37. When this is done the spring 37 may be adjusted 45 more easily by being turned on the screw 35. When the spring reaches the desired position it is allowed to remain in a position outside of the screw 35 with respect to the screw 34 in order that the spring 37 may be adjusted on the screw 34. When the spring 36 reaches the desired position both of the springs 36 and 37 are brought into engagement in a position similar to that shown in Fig. 3. This operation is possible due to the fact 55 that the springs 36 and 37 are resilient and may be sprung with respect to each other in order that they may be separated from engagement as above described.

While I have elected to describe my invention in connection with the specific form of means shown, I do not wish to be so limited inasmuch as other modifications are contemplated within the scope of the claims and the 60 spirit of the invention.

What I claim as new and desire to secure by Letters Patent of the United States is:

1. In combination, a lamp socket having terminals, plug contacts, and conducting strips connecting the lamp socket to the plug contacts, said strips being electrically connected to the lamp socket terminals and to the plug contacts and said strips and plug contacts being adjustable relatively to each other whereby the distance between the lamp 75 socket and the plug contacts may be varied.

2. In combination, a lamp socket having terminals, a plug having plug contacts, and conducting strips connecting the lamp socket to the plug to hold them in spaced relation to each other, said conducting strips being adjustable to vary the distance between the socket and the plug, and said strips being connected to the terminals of the lamp socket and to the terminals of the plug whereby they 80 form a part of the circuit through the lamp.

3. In combination, a lamp socket having strips projecting therefrom, said strips being electrically connected to the lamp socket terminals, and plug contacts carried by said strips and adjustable relatively thereto whereby the distance between the lamp socket 85 and the plug contacts may be varied.

4. In combination, a lamp socket having a pair of strips electrically connected to the socket terminals and projecting therefrom, a plug having a pair of contacts and a pair of strips electrically connected to said contacts and projecting therefrom, and means for fastening said strips together in adjusted 95 overlapping and in circuit-closing relation whereby the distance between the lamp socket and the plug contacts may be adjusted.

In witness whereof, I have hereunto set my hand this 26th day of April, 1928.

CROMWELL A. B. HALVORSON.
